UNITED STATES PATENT OFFICE.

KARL M. HAMILTON, OF CHICAGO, ILLINOIS, ASSIGNOR TO THE BETTENDORF COMPANY, OF BETTENDORF, IOWA, A CORPORATION OF IOWA.

CAR DOOR.

Application filed April 16, 1923. Serial No. 632,280.

To all whom it may concern:

Be it known that I, KARL M. HAMILTON, a citizen of the United States, residing at Chicago, in the county of Cook and State of Illinois, have invented a certain new and useful Improvement in Car Doors, of which the following is a full, clear, concise, and exact description, reference being had to the accompanying drawings, forming a part of this specification.

This invention relates to car doors.

One object of the invention is to provide an end door structure of simple and strong construction, especially adapted for railway cars of the box or house type, so arranged that lumber or other long material may be easily and efficiently loaded into the car.

A further object of the invention is to provide an end door structure of the type indicated, in which the door frame is stamped from sheet metal, and the door associated therewith in such a manner that the same is self-closing, burglar and weather proof.

A still further object of the invention is to provide a door structure of the type indicated wherein a metal threshold is provided, which over-laps the lower wall of the door opening in the end of the car, thus providing means on which the material may be slid while loading.

Another object of the invention is to provide a door construction, wherein the hinge connection is fully protected by a water shed or flashing.

A more specific object of the invention is to provide simple and efficient automatic latching mechanism for holding a door in closed position, having a means associated therewith for receiving a car seal, and wherein additional means is provided for locking the door from the inside of the car to preclude the opening thereof from the outside, when this is desired.

Other objects and advantages of the invention will more clearly appear from the description and claims hereinafter following.

In the drawings forming a part of this specification, Figure 1 is an elevational view of a portion of the end wall of a car, showing my improvements in connection therewith. Fig. 2 is a transverse, horizontal, sectional view, corresponding substantially to the line 2—2 of Fig. 1. Fig. 3 is a vertical,

sectional view, corresponding substantially to the line 3—3 of Fig. 1, the latching mechanism and locking pin being shown in elevation. Fig. 4 is a vertical, sectional view on an enlarged scale, similar to Fig. 3, of the lower portion of the door structure, showing the latching mechanism in section. And Fig. 5 is a detail perspective view of one of the hinge butts.

In the drawings, 10 denotes the end wall of an ordinary single sheath box car, to the outer face of which are secured vertically extending reinforcing Z-bars 11—11. The wall 10 is provided with a rectangular door opening 12 located between the Z-bars, the opposite vertical side walls of the door opening being inwardly spaced from said bars.

The improved door construction, as shown, comprises, broadly, a frame A; a hinged door B; a flashing C; an end plate D; a pair of hinge butt brackets E; a latching mechanism F; and a locking pin G.

The frame A is in the form of a rectangular sheet metal plate, having integral, right angular, vertically extending, outwardly projecting flanges 13 at the opposite sides thereof, rigidly secured to the webs of the Z-bars 11 by any suitable means, such as rivets 14. As clearly shown in Figs. 1 and 2, the flanges 13 extend from the lower edge of the plate to a point approximately in line with the upper wall of the door opening 12. The plate forming the frame A is of such a size as to extend an appreciable distance above and below the upper and lower walls and beyond the side walls of the opening 12, and is provided with a door opening 15 adapted to register with the opening 12.

Along the side and bottom edges of the opening 15, the plate forming the frame A is bent outwardly to provide a continuous bead or rib 16, the bead at the bottom edge terminating in an inwardly projecting horizontal flange 17 extending at right angles to the bottom portion of the plate, and the bead portions at the side edges terminating in inwardly projecting, vertical flanges 18 also extending at right angles to the body portion of the plate. Along the top edge of the opening 15, the plate forming the frame A is bent outwardly to provide a horizontal flange 19, having the outer edge curved downwardly and terminating in a downwardly extending vertical portion 20 overhanging the opening 15. The opposite ends

105
110

of the flange 19 merge with the vertical side portions of the bead 16, thus providing a continuous, outwardly projecting, peripheral wall around the opening 15 of great strength 5 and especially adapted to resist blows. As clearly shown in Fig. 3, the flanges 18 are cut away on diagonal lines at their lower ends, have their upper ends spaced from the upper wall of the opening 15, and partly overlap 10 lap the inner faces of the side walls of the opening 12. The horizontal flange 17 is co-extensive in length with the lower wall of the opening 12, extends inwardly a greater distance than the flanges 18 and forms a 15 threshold protecting the lower wall of said opening. The parts are so proportioned that the outer faces of the flanges 17 and 18 snugly engage the bottom and side walls, respectively, of the opening 12, thereby aiding 20 in holding the frame A in proper position.

The door B is preferably formed of sheet steel, is of generally rectangular outline and has the major portion thereof off-set 25 outwardly, thereby providing a flat, generally rectangular portion 21 having rounded corners; inwardly projecting, continuous top, bottom and side walls 22, 23 and 24, conforming to the outer wall defined by the 30 bead 16 and the flange 19; and a continuous top, bottom and side flange 25 lying in a plane parallel to the portion 21. The top portion of the flange 25 is co-extensive with the width of the door, and is extended 35 upwardly, terminating in a rolled edge 26 enclosing and retaining a hinge rod 27. The hinge rod 27 extends outwardly beyond the side edges of the door a sufficient distance to properly co-act with the hinge 40 butt brackets E.

The flashing C is in the form of a flat plate, co-extensive in width with the door B, having the lower end portion thereof bent outwardly and downwardly, as shown 45 in Figure 3, in loosely embracing overhanging relation to the rolled edge 26 of the door, thereby forming a water shedding flange 28, preventing water from entering between the door and the door frame A. The flat portion of the flashing plate C is 50 interposed between the door frame A and the lower end portion of the end plate D, and has the upper edge thereof in alignment with the upper edge of the door frame. The plate C is secured to the end wall of 55 the car by bolts 29, or any other suitable means, passing through the same and the end plate D. The end plate D extends across the end wall of the car beneath the Z-bars 11 and has the lower edge thereof 60 in abutment with the upper face of the flange 28.

The hinge butt brackets E are of similar construction, one being right and the other 65 left. Each of the brackets E consists of an

upper, flat, plate-like portion 30; a lower portion comprising, an outwardly projecting, downwardly curved flange 31 conforming to the flange 28 and adapted to overlap and cover one of the outer end portions of the same; and a thickened hinge rod supporting portion 32, provided with a bore 38 adapted to receive one end of the hinge rod 27. The portion 32 extends downwardly beyond the flange 31, is formed 70 with an outer curved face and has the rear face thereof, offset with respect to the rear face of the plate as indicated at 33, thereby providing a horizontal shoulder 34. The plate is also provided with a vertically 75 extending, central reinforcing rib 35, which merges with the flange 31 and the hinge supporting portion 32. The hinge butt brackets E, as clearly shown in Figs. 1 and 3, are located at the upper end of the door at 80 the opposite sides of the door opening 15 and are rigidly secured to the end plate D and the flashing C by rivets 36 extending there-through and through the openings 37 in the plate portions 30 of the brackets. The off-set portions 33 of the brackets E project 85 beneath the end plate D with the lower edge of the latter in abutting relation to the shoulders 34. The flanges 31, which overlap and cover the ends of the rolled 90 edge 26 of the door A, form sheds effectively protecting the hinge connection between the rod 27 and the brackets E from the weather.

In assembling the door frame A and the 100 door B, the frame is first assembled with the flashings C and the end plate D. The hinge brackets are then placed in position on the door by engaging the projecting ends of the hinge rod 27 within the bores 38 105 brackets E. The door with the brackets E attached is next placed in proper position on the door frame and the brackets secured in place by the rivets 36.

To automatically latch the door B when 110 the same swings to closed position, the latching mechanism indicated at F is provided. The latching mechanism F comprises a spring pressed, reciprocating latch plunger 39 adapted to co-act with a latch bracket 115 40. The plunger 39 is slidably mounted for reciprocating movement in housing 41, riveted to the lower portion of the door B. The plunger is pressed outwardly by a spring 42 interposed between the upper wall 120 of the housing and the slotted plate 43 locked to the plunger 39 by engagement within the circumferential groove 44 thereof. The plate 43 in addition to serving as an abutment on the plunger co-acting with 125 the spring, also limits movement of the plunger outwardly of the housing. The plunger is provided with a beveled lower end adapted to engage within a recess in the latch bracket 40. As clearly shown in 130

Figure 4, the latch bracket 40 is in the form of an angular plate and is rigidly secured to the end wall of the car by bolts 47 or any other suitable means.

5 It will be evident that when the door swings to closed position, the beveled end 45 of the plunger 39 will engage the edge of the bracket 40, ride upwardly thereon, compressing the spring 42, and will be projected into the opening 46 by the spring 42 when the door reaches its closed position.

10 Means is also provided to permit the attachment of the usual car seal when the door is in closed position to prevent unauthorized opening of the door and theft. This means comprises a laterally extending flange 48 integral with the lower portion of the plunger 39, provided with a seal receiving opening 49 adapted to register with a seal receiving opening 50 in the plate 40, when the door is in closed position.

15 On the inner side of the door, near the bottom thereof, is rigidly secured an angular bracket 51, having the horizontal flange 52 thereof provided with an opening 53 adapted to register with an opening 54 in the flange 17 of the door frame A when the door is in closed position. The openings 53 and 20 54 are adapted to receive the locking pin G, whereby the door may be locked in closed position from the inside independently of the outer latching mechanism, where the end door is not required in loading the car and 25 when the car contains a valuable cargo.

30 In loading box cars with long material, such as lumber, it is the usual practice, especially when the car has been nearly filled, to pass the material into the car through the end door opening, thus subjecting the side and bottom walls of the opening to considerable wear, especially in cars of wooden construction. As the material is slid over the lower door wall in loading, the latter will, ordinarily, be subjected to the greatest 35 amount of damage. By protecting the bottom wall of the opening by a metal sill, and the side walls by metal flanges, as hereinbefore described, all damage to the walls of 40 the opening is minimized.

45 It will be evident that, by forming the door and frame each of one piece construction, the parts are made seamless, water tight and danger of corrosion reduced.

50 It will also be evident that, in addition to producing a weather proof construction by providing the one piece door frame with the projecting bead which surrounds the door opening and co-acts with the top, bottom 55 and side walls of the offset door portion, the bead also forms a strengthening rib which reinforces the entire frame structure.

55 It will be understood that, although the door frame, door and other parts are herein shown and described as being formed of

sheet metal, the invention is not limited thereto, and the parts may be otherwise formed. It will also be appreciated by those skilled in the art that my improvements are equally adaptable to box cars having so-called metal ends and that my improvements, whether applied to all wood or metal end box cars, are equally adapted to new and old cars.

60 I have herein shown and described what I now consider the preferred manner of carrying out the invention, but the same is merely illustrative and I contemplate all changes and modifications that come within the scope of the claims appended hereto.

I claim:

1. In a box car having an end wall provided with an end door opening therein and exteriorly braced by vertically extending beams, the combination with a metal door frame member having an opening adapted to register with said first named opening, said member being provided with portions at each side by which it may be rigidly secured to said beams; of a door movably attached to the door frame member and arranged to close the opening therein.

2. In a car having an end wall formed of wood provided with a door opening, the combination with a unitary sheet metal door frame, having a door opening therein adapted to register with said first named opening, said frame being provided with inwardly bent projecting marginal flanges at the door opening adapted to overlie and protect the walls of said first named opening; of a one piece outwardly opening door exteriorly hinged to said frame and adapted to close said opening.

3. In a car having an end wall provided with a door opening, the combination with a metal door frame comprising a plate-like portion having face contact with said end wall and having a door opening therein adapted to register with said first named opening, said plate-like portion being provided with a bead at the marginal edge of the said opening therein and flanges inwardly projecting from said bead and adapted to overlie and protect the walls of said first named opening; of a one piece door hinged to said frame and adapted to close said opening, said door being provided with an inwardly projecting flange adapted to engage over said bead when the door is swung to closed position.

4. In a car having a wall provided with a door opening, the combination with a metal door frame secured to said wall and having a door opening therein adapted to register with said first named opening, said frame being provided with an outstanding hollow bead at the marginal edge of the opening therein; of a one piece metal door hinged to said frame and adapted to close

- said opening, said door being provided with a flange adapted to exteriorly overlie and abut said bead when the door is closed.
5. In a car having a wall provided with a door opening, the combination with a unitary door frame fixed to said wall and having a door opening therein adapted to register with said first named opening, the margin of said frame surrounding said opening being outwardly offset with reference to said end wall; of a one-piece door adapted to close said opening, said door being provided with a flange adapted to exteriorly over-lap said offset portion when the door is closed.
6. In a door construction, the combination with a unitary sheet metal door frame having a door opening therein surrounded by a continuous, outwardly projecting hollow bead; of a one piece sheet metal door adapted to close said opening, said door being provided with a continuous flange along the bottom and side edges thereof conforming to said bead and adapted to overlie and substantially fit the latter when the door is in closed position.
7. In a door construction, the combination with a unitary door frame having a door opening therein surrounded by a continuous outstanding wall of a one piece door adapted to close said opening, said door having a major portion thereof outwardly off-set to provide a continuous wall conforming to and adapted to exteriorly over-lap said outstanding wall of the frame when the door is in closed position.
8. As an article of manufacture, a sheet metal door frame comprising a flat plate-like portion provided with a door opening, said door opening being surrounded by a continuous rib outwardly projecting from one side of said flat plate, and inwardly projecting flanges formed integral with the lower and side portions of said rib, said ribs extending an appreciable distance beyond the opposite side of said plate.
9. In a car having an end wall provided with a door opening, the combination with a door frame applied to the exterior of said wall and having a door opening therein adapted to register with the first named opening; of an outwardly opening door exteriorly hinged to, and closing against the outer side of said frame; and means overhanging the hinged edge of the door to protect the same from the weather.
10. In a car having an end wall provided with a door opening, the combination with a door frame having a door opening therein registering with the first named opening; of a door having a hinge rod secured to the upper edge thereof; and hinge butts secured to said frame and receiving the opposite ends of said rod, said butts being provided with inwardly extending flanges adapted to overhang the hinge rod adjacent the ends thereof.
11. In a car having a wall provided with a door opening, the combination with a door frame having an opening therein registering with the first named opening; of a door having a hinge rod secured to the upper edge thereof; and hinge butts secured to said frame pivotally receiving the opposite ends of said rod, said butts being provided with inwardly projecting flanges overlapping the side edges of the door and portions of the hinge rod adjacent said edges.
12. In a car having a wall provided with a door opening, the combination with a door frame having an opening therein registering with said first named opening; of a door having hinge pivots projecting from the opposite edges thereof; hinge butt members secured to said frame and each provided with a portion adapted to receive one of said pivots; and a flange forming a continuation of each of said hinge-receiving portions and overlapping the adjacent side edge of the door.
13. In a door for railway cars, the combination with a pivoted hinge connection; of a hinge pin receiving portion; and a water shedding flange for said connection, said flange forming a continuation of said hinge pin receiving portion.
14. In a car having an end wall provided with a door opening, the combination with a door frame having a door opening therein adapted to register with said first named opening; of a door having an upper rolled edge; a pivot rod enclosed by said rolled edge and extending outwardly beyond the opposite edges of said door; a plate secured to the frame above the door and having a flange at its lower edge overhanging said rolled edge; and hinge butt members secured to said frame, said members being provided with bearing parts adapted to receive the opposite ends of said rod, said members being further provided with inwardly projecting flanges adapted to over-lap the opposite ends of the flange on said plate.
15. In a car having an end wall provided with a door opening, the combination with a door frame having a door opening therein adapted to register with said first named opening; of means for hinging said door to said frame including, hinge butt members; and water shedding means over-hanging the hinged edge of the door.
16. In a car having an end wall provided with a door opening, the combination with a door frame having a door opening therein adapted to register with said first named opening; of means for hinging said door to said frame including hinge butt members; and water shedding means over-hanging the hinged edge of the door, including a plate having an outwardly projecting flange and

flanges associated with said hinge butt members and over-lapping said first named flange.

17. In an end door for box cars, the combination with a unitary door frame member having an opening therein and adapted to be applied to the outer face of the car end; of a door hingedly attached along its upper edge to said member and adapted to swing against the outer side of said frame member to close said opening, co-operating inter-fitting means around the side and bottom edges of said opening on the door frame member

and door providing a weather seal when the door is closed; and weather protecting flashing projecting outwardly from the frame and extending over the hinge connection between the door and door frame member. 15

In witness that I claim the foregoing I have hereunto subscribed my name this 11th 20 day of April, 1923.

KARL M. HAMILTON.
